UNITED STATES PATENT OFFICE.

EDMOND GUILBERT, JR., OF WOONSOCKET, RHODE ISLAND.

WEFT STOP MECHANISM FOR LOOMS.

Application filed March 26, 1927. Serial No. 178,586.

The present invention relates to an improvement in weft stop mechanism for looms.

Generally stated, in looms operating on each pick of the lay to throw a plurality of shuttles through a corresponding number of sheds for weaving various sorts of fabrics difficulty has been experienced in providing the loom with weft stopping mechanism for stopping the loom on the failure of a weft. This difficulty has been met particularly in plush looms employing two shuttles thrown through two sheds simultaneously in weaving two superposed fabrics, one in one shed and the other in the other shed, which are subsequently cut to form two pieces of pile fabric. In the latter type of loom it has been proposed to provide a weft detector for feeling of both wefts, but obviously to cause such detector to distinguish between the presence of two wefts and one weft is a matter of difficulty, and the loom should be stopped, of course, upon the failure of either one of the wefts. The present invention contemplates a loom employing a plurality of shuttles, provided with weft detectors for the purpose of detecting failure of any weft, and, in addition, in certain improvements in weft stop mechanism hereinafter described and particularly defined in the claims.

In the accompanying drawings illustrating the preferred form of the invention as applied to plush looms, Fig. 1 is a diagrammatic plan of a portion of a plush loom illustrating the invention; Fig. 2 is a cross-section through the breast beam and the lay, showing the relation of the detectors to the lay and the shuttles carried thereby; Figs. 3 and 4 are respectively an enlarged plan and elevation of one of the weft detectors; Fig. 5 is an enlarged longitudinal medial section in vertical elevation of the rear end of one of the weft detectors and associated parts; and Figs. 6 and 7 are, respectively, top and bottom plans of the top and bottom feelers, respectively.

The illustrated embodiment of the invention is described as follows: The breast beam 10 of the loom carries the detector slides 11 and 12 on opposite sides of the cloth 13 being woven. Supported upon the breast beam is the knock-off rod 14, which carries arms 15 and 16, the upper ends of which are adapted to engage the detector slides 11 and 12 and be pushed forwardly by such slides

to turn the knock-off rod 14. At the shipper side of the loom the knock-off rod 14 is provided with a lever 17, which normally engages the shipper lever 18 when the latter is in its running position, as shown in Fig. 1. When the knock-off rod is turned, the arm 17 presses against the shipper lever 18 and pushes it out of its notch in the bracket 19, and thereby knocks off the loom in the usual manner.

In this plush loom, as is usual, two shuttles 20 and 21 are employed which are picked simultaneously from one side to the other of the loom, each through its separate shed formed in the warp or warps. The warp is indicated at 22, and the two wefts 23 and 24 are diagrammatically shown extending from the selvage across the warp and to the shuttles 20 and 21. In Fig. 1 these two shuttles are shown side by side for the sake of clearness of illustration, whereas in point of fact, one is supported immediately below the other; thus, 21 is received in the lower box and 20 in the upper box of the lay. The detector slide 11 is slidably mounted in the detector slide support or carrier 25. It is normally held in forward position by the usual spring (not shown) on the knock-off rod 14 through the intervention of the arm 15 or arm 16, as the case may be. The lay 26 is provided with a reed 27, and in Fig. 2 the relation of the shuttles to the detector slide is shown. The thread from the upper shuttle enters the upper feeler space 28, and the thread from the lower shuttle enters the lower feeler space 29. The feelers are horizontal forks, the upper feeler 30 being provided with two tines 31 which project rearwardly from a pivot 32, and being provided with a forwardly extending tail 33 having a laterally extended finger 34 which is received in a groove in the weft hammer hook block or control block 35. The slide 11 is provided with a rearwardly projecting wedge-shaped double grid 36. This grid has three grid bars 37. The three grid bars 37 are united at their front ends by a horizontal web 38, which extends to the front end of the grids and conforms in shape to the shape of the grids at this point. It extends forwardly and terminates a short distance back of the point. The two outside grid plates 37 are united by a strut 39. The outside grid bars are provided with shoulders 40 against which the two fillings are adapted to strike at the time of the extreme for-

ward movement of the lay, one filling sliding up on the upper side of the grid plates, and the other filling sliding downward on the lower side of the grid plates, and both being arrested by the shoulders 40 which position the fillings with respect to the feelers. The grid device may be made of a single casting, or may be made of a number of parts. Thus, in the illustrated embodiment the three grid plates are each an integral plate spaced apart at their front ends by two spacer plates which together comprise the part 38. The rear end of the medial grid plate 37 is recessed to receive the strut 39. The device is secured in place by two rivets 41 which pass through them and are riveted in the side walls of the detector slide 11.

Two feeler guards 42 and 43 are provided on the detector slide. These guards extend rearwardly from the upper and lower edges of the detector slide a distance slightly greater than the distance to which the nose of the grid device extends, and afford a protection for the feelers to prevent their accidentally striking a misplaced shuttle. The two filling feelers are of similar construction, and both have their laterally extended fingers projecting in the same direction into grooves in the weft hammer hook block 35.

The hook block or control block 35 is generally of a truncated lozenge form, its vertical height being greatest nearer the rear end than the forward end, and the top and bottom walls inclining toward each other from this point. The weft hammer 44 is pivoted at 45 to the ear 47 on the weft hammer hook block 35. The block is provided in its center with a slot 48 through which extends the pin 49 supported in the side walls of the detector slide 11. As the weft hammer reciprocates, the hook block 35 slides back and forth on the pin. The grooves are cut in one side of the hook block 35. The upper groove 50 receives the finger 34 of the upper filling fork 30, and the lower groove 51 receives the finger 52 of the lower filling fork 53. A hook 54 is provided in this groove 50 which is adapted to engage the laterally extended finger 34 when, during the forward movement of the hook block 35, the filling feeler having made its feeling movement, is not arrested by the filling, in which case the finger 34 rises and engages the hook 54. Then the continued forward movement of the hook block 35 carries the detector slide forward and causes the knock-off rod to be turned and the loom to be stopped. The lower filling fork operates in a similar manner. The weights of the parts of the upper filling fork are such that it normally tends when freed by the entrance of its finger 34 into the wide portion 65 of the groove 50 to turn in the direction to

cause its tines to engage the filling. If they do not engage the filling, the finger rises and engages the hook 54. Similarly, the lower filling feeler or filling fork tends to tip to cause its filling feeling tines to move upwardly to engage the filling, and therefore to cause the finger at the forward end of the fork tail to fall and to engage the lower hook corresponding to the upper hook 54.

The loom as described thus comprises a double filling feeler on each side of the plush being woven, and the wedge-shaped grid device, when the lay approaches, enters between the two fillings extending from the selvage to the adjacent shuttle box, separates those two fillings and causes them to ride, the one up and the other down on the top and bottom surfaces into position against the shoulders 40, where they arrive in timed relation to the movements of the weft hammer hook block, so that they are both free to turn at such filling feeling time, and then in the absence of either one filling or both fillings, the fingers on the filling feeler tails are engaged by a hook or hooks of the weft hammer hook block and the detector slide is pulled forwardly by the further movement of the weft hammer forwardly, thereby stopping the loom.

It is to be observed that in the illustrated embodiment of the invention the failure of either filling on each pick will operate to stop the loom.

The best embodiment of the invention in a plush loom contemplates the use of the double filling feeler on both sides of the cloth being woven, but it is apparent that useful advantages would be obtained by the use of one double filling feeler on one side of the warp only, or by the employment of a filling feeler on one side of the warp to feel of one filling, and a filling feeler on the other side of the warp to feel of the other filling.

The particular construction of weft detector illustrated and described herein is of value, and may be used in any form of loom. Thus, as the weft hammer hook block or control block 35 moves forward, it releases the tail of the fork when the wide part of the groove 50 presents itself to the tail 34 of the fork. Then the fork, which normally stands only slightly above the filling, is permitted to engage the latter owing to the widening of the groove. If filling is present, the latter supports the fork with the tail 34 in position to engage the inclined portion below the hook 54. Then as the weft hammer hook block continues its forward movement, this inclined surface engages the tail of the fork and lifts it (in the case of the upper fork, and depresses it in the case of the lower fork), and releases the pressure of the fork upon the filling, which is thereby freed from the fork when the shuttle is

thrown. In short, the construction is one in which the fork is pressed against the filling with very slight pressure and without the usual blow which occurs when in an ordinary loom the grid on the lay carries the weft violently against the depending tine of an ordinary fork. The fact that this construction is one in which the fork is applied with such light pressure to the filling 5 makes the detector available for use with extremely light filling such as rayon, or other artificial silk, as such delicate engagement of the fork with the rayon will not injure or break it whereas, with the ordinary 10 fork, the blow of the rayon carried by the grid against the fork tines sometimes causes a severing of some of the filaments of the rayon filling.

It is immaterial, of course, whether the 15 loom to which this invention is applied uses one or more warp beams to supply the warp used in weaving. In some plush looms two warp beams are used, the one supplying the warp for one shed, and the other supplying 20 the warp for the other shed. In other plush looms one warp is used.

While claims have been included directed 25 to the feeler construction, it is intended to cover a feeler provided with only one fork, certain features of the feeler being as well 30 adapted for a single fork detector as a double fork detector.

While the invention has found its principal use in plush looms employing two shuttles moving simultaneously in the same direction through two sheds, it is apparent 35 that the invention may also be used in connection with looms employing two shuttles thrown in opposite directions at the same 40 time, as in some looms, in which case a single feeler would be employed on each side of the loom which would feel on one pick of the thread from one shuttle, and on 45 the next pick of the thread from the other shuttle.

Having thus described the invention, what is claimed is:

1. A plush loom having, in combination, a lay having two shuttles for simultaneous 50 picking movement, two weft detectors on one side of the loom, one detector having a down-feeling fork to feel the weft from the upper shuttle, and the other detector having an up-feeling fork to feel the weft from the 55 lower shuttle, stop mechanism, and connections between each detector and the stop mechanism to stop the loom on the failure of weft from either shuttle.

2. A plush loom having, in combination, a lay having two shuttles for simultaneous 60 picking movement, a weft detector on one side of the loom supported in horizontal position, means for controlling the detector having provision for supporting it from feeling 65 movement at all times except when the

weft extends from the adjacent selvage to the shuttle on the same side of the loom with the detector, stop mechanism, and connections between the detector and the stop mechanism to stop the loom upon failure of 70 the weft in either shuttle.

3. A plush loom having, in combination, a lay having two shuttles for simultaneous picking movement, two weft detectors on one side of the loom each supported in position 75 to feel the weft from one of the shuttles, guides for presenting the wefts from each shuttle to each detector, means having provision for holding the detectors from filling 80 feeling movement at all times except when the weft extends from the selvage to the shuttle on the same side of the loom, stop mechanism, and connections between the detector and the stop mechanism to stop the loom upon failure of the weft in either 85 shuttle.

4. A plush loom having, in combination, a lay having two shuttles for simultaneous picking movement through two adjacent superposed sheds, two weft detectors on one 90 side of the loom supported to feel by movements toward each other, a guide for separating the two wefts and presenting them to the detectors, stop mechanism, and connections between each detector and the stop 95 mechanism to stop the loom on the failure of weft from either shuttle.

5. A weft detecting mechanism for looms having, in combination, a detector slide, a weft fork pivoted on the slide having tines 100 extending horizontally rearwardly and a tail extending horizontally forwardly from the pivot, having at its end a laterally extended finger, a grid mounted on the slide, a weft hammer, a weft hammer hook mounted on 105 the weft hammer provided with a groove to receive the laterally extending finger of the weft fork tail, such groove having two narrow end portions for preventing movement of the fork and a widened portion permitting 110 vertical movement of the fork in the absence of weft, such widened portion being provided with a hook to engage the laterally extended finger on the tail of the weft fork in the absence of weft, stop mechanism, and 115 connections between the detector slide and the stop mechanism to stop the loom on the failure of weft.

6. A double fork weft detector for plush 120 looms having, in combination, a pair of horizontally arranged oppositely movable filling forks, and a detector slide upon which the forks are mounted provided with guards rearwardly extended from the slide to prevent engagement of the forks with a misplaced shuttle.

7. A weft detector mechanism for looms comprising a pivotally mounted filling fork having rearwardly extended filling feeling 130 members and a forwardly extended tail, a

support for the fork upon which it is pivoted, and having a rearwardly extended guard for preventing accidental striking of the shuttle by the fork.

5. 8. A loom having, in combination, a lay having two shuttles for simultaneous superposed picking movement, two superposed weft detectors on one side of the loom, the upper one having a down-feeling fork and
 10 the lower one having an up-feeling fork to feel the wefts from the upper and lower shuttles respectively, stop mechanism, and connections between each detector and the stop mechanism to stop the loom on the failure of weft from either shuttle.

15. 9. A loom as defined in claim 8 provided with two superposed weft detectors on both sides of the loom.

10. 10. A loom having, in combination, a lay
 20 having two shuttles for simultaneous superposed picking movement, a pair of superposed weft detectors on one side of the loom having oppositely feeling weft forks to feel the weft from the upper and lower shuttles
 25 respectively, stop mechanism, and connec-

tions between each detector and the stop mechanism to stop the loom on the failure of weft from either shuttle.

11. A weft detector having, in combination, a guide block, a grid, a feeling fork, a
 30 guard, and a vibrating control block having a groove comprising first a narrow portion, then a wide portion to which the narrow portion leads, a locking hook, a lifting incline, and finally a straight narrow portion, 35 said fork having a finger extending into said groove to control the feeling movement of the fork.

12. A loom having, in combination, a lay having two shuttles for simultaneous picking movement, two weft detectors one above the other on the same side of the loom, and a control block which automatically causes the upper weft fork to feel downward 40 against the upper weft and the lower weft fork to feel upward against the lower weft.

In testimony whereof I have signed my name to this specification.

EDMOND GUILBERT, JR.
